UNITED STATES PATENT OFFICE.

PATRICK J. DUGGAN, OF BOSTON, MASSACHUSETTS.

BINDER FOR BRAID-ROLLS.

SPECIFICATION forming part of Letters Patent No. 250,428, dated December 6, 1881.

Application filed October 17, 1881. (No model.)

To all whom it may concern:

Be it known that I, PATRICK J. DUGGAN, of Boston, in the county of Suffolk and State of Massachusetts, have invented new and useful 5 Improvements in Binders for Braid-Rolls, of which the following is a specification.

My invention relates to a device for holding braid when the same is coiled upon the spools; and it consists in so constructing the device for 10 holding braid that it shall, when loose, constitute not only a holding device, but also a device which will furnish an elastic tension-loop, so that the tape cannot withdraw from it except by force applied for the purpose of 15 withdrawing it. I attain these results by the mechanism illustrated in the accompanying drawings, in which—

Figure 1 is a perspective view, showing a coil of braid with my device attached. Fig. 2 20 shows the device as it appears when not connected with the spool. Fig. 3 shows the device as it appears when connected with the spool.

To construct my device, I bend a piece of 25 wire as shown in the drawings, and indicated

in Figs. 2 and 3 by the letters b B B' B^2 B^3 B^4 B^5 B^6 , forming an open loop, as shown at C C' in Fig. 2, when not attached to a spool, and forming a partially-closed loop, as shown at C and C' in Fig. 3. This closing of the loop C 30 C' is caused by opening the parts B B^6 , this action serving to spring or throw upward the parts of the wire marked b^2 b^3 , Fig. 3, thus pinching with a spring-like tension the tape in the loop C C' . The coil B^3 in the wire serves 35 to give the device more elasticity, and thereby better tension qualities. The coil also serves as a handle to be used in the rewinding of the tape.

Having thus described my invention, what 40 I desire to secure by Letters Patent is—

A braid-binder consisting of a single piece of wire bent to form the members b B b^2 B' B^2 B^3 B^5 b^3 B^6 b' , all arranged and operating together substantially as described, and for the 45 purpose set forth.

PATRICK J. DUGGAN.
